UNITED STATES PATENT OFFICE

165,472

CHAIR FOR VIEWING TELEVISION

Jacob C. Lamm, Baltimore, Md.

Application August 8, 1951, Serial No. 16,205

Term of patent 14 years

(Cl. D15—8)

To all whom it may concern:

Be it known that I, Jacob C. Lamm, a citizen of the United States of America, residing at city of Baltimore, State of Maryland, have invented a new, original, and ornamental Design for a Chair for Viewing Television, of which the following is a specification, reference being had to the accompanying drawing, forming a part thereof.

Figure 1 is a front elevation of a chair for viewing television embodying my new design;

Figure 2 is a side elevation thereof; and

Figure 3 is a top plan view of the same.

I claim:

The ornamental design for a chair for viewing television, as shown.

JACOB C. LAMM.
